US0D1063079S

(12) **United States Design Patent** (10) **Patent No.:** **US D1,063,079 S**
(45) **Date of Patent:** **** Feb. 18, 2025**

(54) **PHYSIOLOGICAL MONITORING DEVICE**

(71) Applicant: **iRhythm Technologies, Inc.**, San Francisco, CA (US)

(72) Inventors: **Jeffrey Joseph Abercrombie, II**, Oakland, CA (US); **James Kihyun Lee**, Los Gatos, CA (US); **Thomas Burnell Reeve, III**, San Francisco, CA (US); **David Haldane**, Vallejo, CA (US)

(73) Assignee: **iRhythm Technologies, Inc.**, San Francisco, CA (US)

(**) Term: **15 Years**

(21) Appl. No.: **29/848,592**

(22) Filed: **Aug. 3, 2022**

(57) **CLAIM**

The ornamental design for a physiological monitoring device, as shown and described.

DESCRIPTION

FIG. 1 is a top, front, and right-side perspective view of a physiological monitoring device showing our new design; and,

FIG. 2 is a bottom view thereof.

Broken lines in the drawings depict portions of the physiological monitoring device that form no part of the claimed design.
